ROCKET MOTORS

Frederick James Porcher, Edgbaston, England, assignor to Imperial Chemical Industries Limited, London, England, a corporation of Great Britain

Filed Feb. 11, 1959, Ser. No. 792,224

Claims priority, application Great Britain Nov. 25, 1958

4 Claims. (Cl. 60—35.6)

This invention is concerned with rocket motors of the kind in which solid propellant is used.

This application is a continuation-in-part of my application Serial No. 641,423, filed Feb. 20, 1957, now abandoned.

Long-burning rocket motors employ either a slow-burning propellant burning radially or a relatively fast-burning propellant burning cigarette-wise. Limitations on radial dimensions and difficulty of producing propellants having a burning rate suitable for the dimensions and burning-time factors militate against the radial-burning configuration. On the other hand, large centre of gravity changes occurring during burning of the simple cigarette configuration are also objectionable. It has been proposed to overcome the latter disadvantage by using a cigarette-burning configuration in which a single charge burns from both ends simultaneously, the gases generated at the head-end of the motor passing via an integral axially-located transfer tube to the nozzle-end of the motor. But here again other disadvantages arise, in that the supporting means holding the charge in position within the rocket, and the obturation means adapted to prevent flow of hot gases over the circumferential surface of the charge, both of which are usually located at or towards the ends of the charge, are quickly rendered useless in the early stages of burning. Consequently, the charge soon becomes free to move, and the hot gases from the head end are allowed to pass between the charge and the casing heating the latter, and igniting the circumferential surface of the charge. Moreover, the transfer tube, which transfers the gases from the head end to the nozzle end of the rocket motor must be of material which is not only heat-resistant but also capable of resisting the erosive action of the hot gas flow. Those materials which are sufficiently heat- and erosion-resistant are difficult to bond to the propellant charge and also their respective coefficients of expansion are different. The latter factor is significant because the motors have to be temperature-cycled several times at temperatures ranging alternately from arctic to tropical conditions, and in the course of thus testing, the charge frequently separates from the transfer tube, again with the result that the charge is liable to be ignited unintentionally at a surface other than an end-face.

According to the present invention, a rocket motor comprises a solid propellant charge secured in the motor casing and a second solid propellant charge secured in the casing in such manner as to prevent continuous flow of propellant gas over the outer surface of the second charge between said surface and the casing, said second charge being spaced from the first-mentioned charge towards the rear end of the motor whereby the adjacent end surfaces of the two charges are spaced apart from each other, said adjacent end surfaces being the surfaces at which the charges burn when ignited, i.e. ignition end surfaces, each charge having that part of its surface exposed to the gas, except the ignition end surface, covered by ignition-preventing means, and means for igniting the

2

ignition end surfaces, a transfer tube for directing to exhaust propellant gas generated in the space between the charges, said tube being located in a passage in the second charge which extends from end to end thereof and being so positioned in said passage that all the propellant gas directed to exhaust passes into said tube without substantially eroding the ignition-preventing means in said passage, a propellant gas flow path being provided for each charge for equalising the pressure on both ends of the charge and being such that the propellant gas which pressurises the end of the charge opposite to its ignition end is substantially static gas, the flow path for the second charge being by way of a clearance between the transfer tube and wall of said passage, the transfer tube and motor casing being connected rearwardly of the second charge by a gas-tight joint.

In one embodiment of the invention, two propellant charges are employed in axial alignment within the motor casing, and are spaced apart. In part of the space between adjacent ends of the two charges (which are the ignition end surfaces) there is disposed an ignition means which when fired ignites substantially simultaneously both the ignition end surfaces. The second or rear charge has a bore through which extends a gas transfer tube, the said tube serving to convey all the hot gases from both charges to the atmosphere external to the rocket through an aperture in the rear end wall of the casing. The two charges are secured to the end walls of the casing at their respective forward and rearward ends and the securing means thus remain operative substantially throughout the burning period. Moreover, the transfer tube is secured to the wall of the aperture in a gas-tight manner, and is the sole exit for the hot gases so that all the gases from both portions of the charge are caused to flow through the entire length of the tube and escape therefrom only via the motor nozzle.

The second charge is supported against differential gas pressure on the ends of the charge by reason of the fact that some propellant gas initially flows through the clearance between the transfer tube and charge into a space behind the charge where it remains as substantially static gas in contact with the rear end thereof.

The forward charge may be supported against differential gas pressure in the same way, i.e. by the use of a transfer tube to duct the propellant gas to the end of the charge remote from its ignition end. Preferably, however, the forward charge is solid throughout and the propellant gas flow to support it is through an annular clearance between the outer surface of the charge and the inner surface of the motor casing. To enable the gas to have access to the forward end of this charge the means supporting the charge in the casing is provided with a passageway to let the gas through.

A rocket motor in accordance with the invention has several advantages over hitherto proposed rocket motors. For example, bonding of the charge to the transfer tube and the difficulty of ensuring that the bond remains good after the temperature cycle test are avoided. Moreover, since all the hot gases must pass through the transfer tube, and there is no continuous flow of hot gases through the space between the charge and the casing or the space between the charge and the transfer tube, the normal inhibiting means are adequate to prevent uncontrolled burning of the charge. This means that the centre of gravity shift of the motor during burning can be controlled to an acceptable limit. Since there is no gas-flow over the internal surfaces of the end walls of the casing, the insulation of the end walls of the casing can be of a simple kind.

The preferred embodiment of the invention is illustrated in the accompanying drawings of which:

Figure 1 is a vertical section of the motor and

Figure 2 is a similar section of the nozzle end of the motor.

The nozzle is connected to the transfer tube shown in Figure 1 either directly or by means of an extension of the transfer tube or by a separate blast tube (not shown).

Referring now to Figure 1, the numeral 1 indicates a cylindrical motor casing having forward and rear end closures 2, 3 secured thereto by screws 4. Disposed within the casing 1 at the forward end is a first propellant charge 5 and spaced therefrom in the axial direction towards the rear end of the casing 1 is a second charge 6, the remote ends of the two charges being spaced from their respective end closures as shown. The adjacent surfaces 7, 8 of the two charges 5 and 6 are the ignition end surfaces and each charge is covered on all of its surface other than the ignition end surface with ignition-inhibiting material such as cellulose acetate.

Referring now to the first charge, the inhibiting material takes the form of layers 9 and 10 and a ferrule portion 11. The ferrule 11 is provided with an annular groove 12 and the charge 5 is supported in position by means of a grain hold-back ring 13 screwed to the end closure 2, the grain hold-back ring 13 having a claw portion 14 which engages in the groove 12 in the ferrule 11. A shock-absorbing ring 15 is located in the groove 12 and provides a gas-tight joint between the claw portion 14 and the ferrule 11.

The grain hold-back ring 13 is designed to leave a clearance 16 between itself and the ferrule 11 and is provided with a number of circumferentially spaced holes 17. As shown, there is a small gap 18 between the outer surface of the charge 5 and the inner surface of the casing 1 and the arrangement thus provides a flow path for propellant gas from the space between the charges, along the annular gap 18, through the holes 17 and clearance 16 and into the space 19 between the forward end face of the charge 5 and the end closure 2. The end closure 2 is plugged at 20 and the space 19 therefore provides a dead end for the gas flow.

The second charge 6 is also provided with layers of inhibiting material and a ferrule of inhibiting material, the reference numerals for these parts being those employed for the corresponding parts of the first charge 5. The charge 6 is secured in position in a similar manner to the charge 5 by means of a grain hold-back ring 21, the grain hold-back ring 21 differing from the ring 13 for the charge 5 in that it has no holes corresponding to the holes 17. A gas-tight seal 22 is interposed between the ring 21 and end closure 3 and it will thus be seen that the charge 6 is supported at its outer surface in a manner which will prevent continuous flow of gas along the gap between the outer surface of the charge 6 and the inner surface of the casing.

The charge 6 is provided with a central passage extending from one end of the charge to the other and in which is located a transfer tube 23. The surface of the charge 6 in the passage is covered with ignition-preventing material 24 and there exists a clearance 25 between this material 24 and the transfer tube 23.

The transfer tube 23 passes out of the casing through the end closure 3 and is fitted in the end closure 3 in a gas-tight manner by means of a plug 26. The tube 23 is therefore connected to the motor casing rearwardly of the charge 6 by a gas-tight joint and the space 27 between the charge 6 and end closure 3 is a dead-end for propellant gas flowing therein from the clearance 25.

Mounted at the inner end of the transfer tube 23 and in the space between the two charges 5, 6 is an igniting means 28 having leads 29 which extend through the transfer tube 23 externally of the motor to an electrical source (not shown). The transfer tube is connected at its external end to a conventional motor nozzle 30 as shown in Figure 2.

To start the motor the igniting means 28 is energised

through the leads 29 to cause ignition of the charges 5 and 6 on the ignition end surfaces 7 and 8. The igniting means 28 soon burns away and disintegrates leaving the forward end of the transfer tube 23 open for the admission thereto of propellant gas generated in the space between the two charges. When the charges start to burn there is an initial flow of propellant gas along the annular gap 18 between the charge 5 and the casing, through the flow path described above and into the space 19. Similarly there is an initial gas flow into the space 27 behind the charge 6 but in this case the flow path is by way of the clearance 25. Both charges are thereby supported at their ends remote from the ignition ends by means of substantially static gas which has negligible erosive effect on the ignition-inhibiting material.

The main bulk of the gas generated is conveyed through the transfer tube 23 towards the nozzle 30 and the position of the forward end of the transfer tube 23 is such that no erosion of the ignition-preventing material 24 in the passage in the charge 6 occurs.

As the charges continue to burn, the burning surfaces recede from one another maintaining the centre of gravity of the system in a practically constant position. Since the charges are at all times supported against differential gas pressure there is no cracking of the charges with consequent introduction of new ignition surfaces and loss of control.

For convenience the invention has been described with reference to the drawing of a rocket motor containing only two charges of propellant material. It will be appreciated, however, that the invention may be employed with three or more charges of propellant material. In such arrangements any number of charges may be placed in the motor using the construction and arrangement described above for the second charge. That is to say the charges will be traversed through by transfer tubes and will be pressurised at the ends opposite to their ignition ends by means of static gas in the manner aforementioned. In this case some of the transfer tubes will be fixed to some internal bulkhead and will not be connected directly to the nozzle but will be used to transfer gas from one chamber to another in the motor. It will be understood that the charges will be arranged in accordance with the maximum acceptable centre of gravity change during burning for the motor as a whole, the disposition of the ignition ends of the charges being such that gas flows into a transfer tube without eroding the surface of its adjacent charges. The employment of more than two charges is sometimes dictated by the need to using a casing which has a reduced cross-section at one or more positions along its length.

I claim:

1. A rocket motor comprising a casing, first and second propellant charges mounted in said casing in spaced apart relationship, a gas tight joint between said second charge and said casing whereby passage of gas over the outer circumferential surface of said second charge is prevented, the facing surfaces of said propellant charges constituting ignition end surfaces and the other surfaces of said charges being covered with ignition-inhibiting material, a passage through said second charge, a gas transfer tube extending through said passage and through the casing, a gas tight joint between said transfer tube and said casing, said passage being larger than said gas transfer tube whereby gases generated in the space between said charges may flow between said gas transfer tube and said second charge to the remote end of said second charge to provide a cushion of substantially static gas to equalize the pressure on said second charge, means affording a flow path around the outer circumferential surface of said first charge for permitting gas to flow to the remote end of said first charge to provide a cushion of substantially static gas to equalize the pressure on said first charge, and means for igniting the ignition end surfaces of said charges substantially simultaneously.

2. A rocket motor as defined in claim 1, wherein said first propellant charge is located at the head end of the motor and is solid throughout, and the flow path for said first charge is by way of a gap between the charge and the casing and through a passage provided in the means by which said charge is mounted in the casing.

3. A rocket motor comprising a casing, first and second propellant charges mounted in said casing in spaced apart relationship, the facing surfaces of said propellant charges constituting ignition end surfaces and the other surfaces of said charges being covered with ignition-inhibiting material, a passage through said second charge, and a gas transfer tube extending through said passage, said passage being larger than said gas transfer tube whereby gases generated in the space between said charges may flow between said gas transfer tube and said second charge to the remote end of said second charge to provide a cushion of substantially static gas to equalize the pressure on said second charge.

10

4. A rocket motor as defined in claim 3, including a gas tight joint between said second charge and said casing whereby passage of gas over the outer circumferential surface of said second charge is prevented, and means affording a flow path around the outer circumferential surface of said first charge for permitting gas to flow to the remote end of said first charge to provide a cushion of substantially static gas to equalize the pressure on said first charge.
